J. H. RAND

INDEX DEVICE

Filed Feb. 11, 1922

FIG. 1

FIG. 2

FIG. 3

Inventor;
James H. Rand,
by Robert Robert & Cushman,
his attys.

UNITED STATES PATENT OFFICE.

JAMES H. RAND, OF NORTH TONAWANDA, NEW YORK.

INDEX DEVICE.

Application filed February 11, 1922. Serial No. 535,717.

To all whom it may concern:

Be it known that I, JAMES H. RAND, a citizen of the United States of America, and resident of North Tonawanda, in the county 5 of Niagara and State of New York, have invented new and useful Improvements in Index Devices, of which the following is a specification.

This invention relates to card indexes and 10 more particularly to card indexes of the type in which a plurality of cards are mounted in an upright frame in overlapping relationship so that the lower margins of the cards are visible and so that cards may be swung 15 apart to display the data on the overlapped portions.

According to this invention a sheath of celluloid or other suitable material is adapted 20 to extend over the margin of an index card or the like in such manner that the card and sheath are slidable longitudinally of each other and a stop is provided at the end of the margin to prevent accidental displacement of the card from the sheath or 25 vice versa, the stop preferably being on the sheath and preferably forming an integral part thereof. The sheath is in the form of a channel having adjacent sides and one of the sides may be folded inwardly to interlock 30 with the card. The aforesaid stop is preferably formed by turning the end of one side inwardly across the mouth of the channel. The side of the channel which is not inturned at the end as aforesaid may 35 terminate short of the other side to provide an opening through which the card may be slipped into the sheath; but when the sheath is made of celluloid or other flexible material the channel may be spread open sufficiently 40 to permit the insertion of the card past the aforesaid stop without terminating the one side much, if any, short of the other side.

In the accompanying drawings which 45 illustrate the invention,

Fig. 1 is a rear view of one of the devices;

Fig. 2 is a section on the line 2—2 of Fig. 50 1; and

Fig. 3 is a section on the line 3—3 of Fig. 1.

The embodiment of the invention chosen for the purpose of illustration comprises, in general, the card C and a sheath S fitting

55 over the lower margin. The card C may be provided with suitable means for mount-

ing it in the frame with other cards, the means shown in the drawing comprising a mounting strip M having projecting ends adapted to fit in slots in the holder frame, 60 the mounting strip M being hinged to the card C by means of a strip of fabric H.

The sheath S is channel-shaped as shown in Fig. 2, the two sides s and s' of the channel being substantially parallel. The side s is folded inwardly as shown at s'' in Fig. 2 to interlock with a fold c on the lower end of the card C. As shown in Fig. 1 the side of the channel which is folded inwardly terminates short of the other side to provide 70 lateral openings O and O' near the ends of the sheet. The other side s' of the channel is inturned at each end to form stops I in line with the channel.

The sheath S is preferably made of thin 75 celluloid sheet material, the celluloid preferably being transparent so that indicia on the lower margin of the card is visible through the sheath.

When the sheath S is made of celluloid or 80 other flexible material the sides s and s' may be spread apart sufficiently to permit the insertion of the card into the sheath past the inturned ends I, but this operation is facilitated by providing the openings O and 85 O'. If the material of the sheath S is too stiff to permit spreading of the sides, the card may be inserted through either of the openings O and O' by slightly flexing the card. 90

By virtue of the interlocking folds c and s'', the sheath and card cannot be separated transversely; and accidental displacement of the card and sheath longitudinally of each other is prevented by the inturned ends 95 I which lie in the direct path of the card.

I claim:

1. An index device comprising a card, a sheath extending over the margin of the card, the card being slidable in the sheath 100 longitudinally of the margin, and a stop at the end of said margin to prevent accidental displacement of the card from the sheath.

2. An index device comprising a card, a sheath extending over the margin of the card, the card being slidable in the sheath 105 longitudinally of the margin, and a stop on each end of the sheath in the direct path of the card to prevent accidental displacement of the card longitudinally of the sheath.

3. An index device comprising a card, a sheath extending over the margin of the

- 2
- card, the card and sheath having an interlocking relationship permitting relative longitudinal sliding of the parts relative to each other, and one of the parts having an integral stop in the direct path of the other part to prevent accidental displacement of the parts longitudinally of each other. 5
4. An index device comprising a card, a sheath extending over the margin of the 10 card, the card and sheath having an interlocking relationship permitting the card to slide longitudinally of the sheath, and the sheath having an integral stop at each end to prevent accidental displacement of the 15 card longitudinally of the sheath.
5. An index device comprising a sheath having a channel to receive the margin of a card in sliding relationship longitudinally of the channel, the channel having a side 20 opening near one end through which the card may be inserted and having stops at the ends of the channel to prevent accidental displacement of the sheath.
6. An index device comprising a sheath 25 having a channel to receive the margin of a card in sliding relationship longitudinally of the channel, one side of the sheath ter-
- minating short of the end of the sheath to permit the insertion of a card, and the other side having an inturned end to retain the 30 card in the channel. 35
7. An index device comprising a sheath having a channel to receive the folded margin of a card in sliding relationship longitudinally of the channel, one side of the sheath being folded inwardly to interlock with the card and the other side of the sheath having an inturned end to retain the 40 card in the channel.
8. An index device comprising a sheath 45 having a channel to receive the folded margin of a card in sliding relationship longitudinally of the channel, one side of the sheath being folded inwardly to interlock with the card and the other side of the sheath having an inturned end to retain the 50 card in the channel, the sheath being flexible to permit the channel to be spread open sufficiently to insert the folded margin of the card into the channel past said inturned end.

Signed by me at North Tonawanda, N. Y.
this eighth day of February 1922.

JAMES H. RAND.
